US00D526957S

(12) **United States Design Patent** (10) **Patent No.:** **US D526,957 S**
Croley et al. (45) **Date of Patent:** **** Aug. 22, 2006**

(54) **MOBILE DEVICE BATTERY**

(75) Inventors: **Curt Croley**, Stony Brook, NY (US);
Carl Theleman, East Islip, NY (US);
JaeHo Choi, Whitestone, NY (US)

(73) Assignee: **Symbol Technologies, Inc.**, Holtsville, NY (US)

(**) Term: **14 Years**

(21) Appl. No.: **29/238,386**

(22) Filed: **Sep. 14, 2005**

(51) **LOC (8) Cl. 13-02**

(52) **U.S. Cl. D13/103**

(58) **Field of Classification Search** D13/102-106,
D13/110, 118-119, 184; 429/96-100, 163,
429/176

See application file for complete search history.

(57) **CLAIM**

The ornamental design for a mobile device battery, as shown and described.

DESCRIPTION

FIG. 1 is a front view of a mobile device battery showing our new design;

FIG. 2 is a side view thereof;

FIG. 3 is a top view thereof;

FIG. 4 is a bottom view thereof; and,

FIG. 5 is a back view thereof.

The broken lines shown in FIGS. 1-5 are included for illustrative purposes only and form no part of the claimed design.

1 Claim, 2 Drawing Sheets

FIG. 3

FIG. 1

FIG. 2

FIG. 4

FIG. 5
